UNITED STATES PATENT OFFICE.

WILLIAM HOWARD PALMER, OF FORT SCOTT, KANSAS.

FORCED-DRAFT-FURNACE GRATE.

266,971.

Specification of Letters Patent. Patented May 24, 1910.

Application filed January 21, 1909. Serial No. 473,404.

To all whom it may concern:

Be it known that I, WILLIAM H. PALMER, a citizen of the United States, residing at Fort Scott, Bourbon county, Kansas, have invented certain new and useful Improvements in Forced-Draft-Furnace Grates; and I do hereby declare the following to be a full, clear, and exact description of the invention, such as will enable others skilled in the art 10 to which it appertains to make and use the same.

This invention relates to certain improvements in furnaces and relates more particularly to improvements in force draft grates; 15 and the objects and nature of my invention will be readily understood by those skilled in the art in the light of the following explanation of the accompanying drawings illustrating what I now consider my preferred embodiments from among other arrangements and formations within the spirit and scope of my invention.

The invention consists in certain novel features in construction and in combinations 25 and arrangements of parts and formations as more fully and particularly set forth hereinafter.

Referring to the accompanying drawings;—Figure 1, is a cross section through a 30 portion of a furnace bed or grate constructed in accordance with my invention. Fig. 2, is a top plan view of a grate bar thereof. Fig. 3, is a side elevation of one of the grate bars detached. Fig. 4, is a vertical longitudinal 35 section through a portion of said bar. Figs. 5 and 6, are detail views of the rings and caps of the air blast outlets. Figs. 7 and 8 are views illustrating a modified formation of air blast openings and plates.

My improved furnace bed or grate is particularly intended to receive fuel in a finely divided state such as slack or the like and to this end is constructed without openings or 45 passages therethrough except for blasts of air directly upward into the fuel on the bed. The bed is what might be termed closed or solid, inasmuch as no openings or spaces are provided through which fuel can drop or escape, the object being to necessitate combustion of all fuel introduced into the furnace onto the grate as the fuel cannot escape except by the door opening through which the fuel was introduced. To this end I form 50 the furnace bed or grate of a suitable number of spaced and usually parallel hollow

grate bars (generally indicated by 1, in Fig. 1,) and intervening packing and supporting means throughout the bed completely closing the spaces between the grate bars, and supporting the grate bars.

Hollow grate bar carrying ledges or other suitable supports are provided along the furnace walls surrounding the furnace bed or grate, and at intermediate points between said walls. For instance in the particular example illustrated, I show parallel I-beams 60 2, horizontally arranged within the furnace and at their ends supported by opposite furnace walls or in any other suitable manner. These beams can extend longitudinally of 65 the furnace, that is, from the front to the rear thereof, and such distance apart that the grate bars can rest on the beams and depend between the same and preferably so that each intermediate beam will receive and 70 partially carry two grate bars.

The spaces between the upper portions of the grate bars are closed and filled in by suitable packing material such for instance as refractory material and to this end, I 75 show fire or other bricks or refractory material blocks 3, laid transversely of the spaces between the grate bars and a fine packing 4, of suitable sand closing interstices between the bricks and the bars and covering the 80 bricks about to the level of the top faces of the grate bars. It will hence be observed that the grate bars are stationary or fixed, and the grate or furnace bed as an entirety 85 is fixed or stationary and the closed top 90 surface thereof is made up of the top faces of the grate bars and the intervening surfaces of packing or filling material so that it is not possible for fuel to waste by dropping or falling through said furnace grate 95 or bed.

Each grate bar is longitudinally hollow and is normally closed except for the blast or compressed air inlet and the top blast outlet openings. Each bar is preferably 100 composed of two longitudinal sections, the lower or supporting section 5, and the upper or fuel supporting section 6. The lower section is usually composed of a longitudinal trough-like casting open at the top and 105 closed at the ends, sides and bottom and with its sides inclining or converging toward the flat bottom wall. This lower section is formed with an internal horizontal supporting seat or ledge 50, along the inner faces 110

of its sides and ends and a comparatively short distance below the flat top edges 51, of its sides and ends. The lower section is also formed with an exterior horizontal 5 projecting supporting flange or ledge 52, extending along the opposite sides and ends of the section and arranged near the top of the section say about in the horizontal plane of the internal supporting ledge 50. The 10 formation of this lower section is such that the exterior side ledges 52, will rest on the top faces of two adjacent beams 2, with the section depending between such beams and with the ledge 52, at the ends of the bar resting on supports at the front and rear furnace walls. The lower section is formed at one end with a depending nipple or other connection 53, to receive the blast pipe or other source of compressed air for delivery 15 to the grate bar. The lower section can also be formed with a series of vertical ash discharge holes or perforations 54, drilled through the flat floor of the section and normally closed by a flat slide 55, arranged 20 longitudinally within and resting on the floor of the section and allowed a limited longitudinal movement therein to close said openings or to bring them into alignment or registration with corresponding openings 25 56, through the slide for the purposes hereinafter explained. This slide can be confined and limited in its movement by bolt 56, passing through longitudinal slot 57. The slide can be reciprocated through the 30 medium of its perforated lug 58, depending through slot 59.

The top or fuel supporting section 6, of the grate bar is usually formed by a casting in the shape of an inverted trough open at 40 the bottom and having a top wall, and closed side and end walls. The side walls and end walls are vertical and usually parallel respectively. The lower side of this upper section is formed to slip or fit down 45 into the open upper end of the lower or supporting section until its lower edge seats on the internal supporting ledge 50 of the lower section, whereby the top section is supported and upheld. An exterior air 50 tight joint 60, can be formed between the sections by introducing cement between the overlapping outer surfaces of the upper section and inner surfaces of the lower section above the seat 50, whereby the two sections are secured together to form the hollow bar.

A longitudinal series of separate and spaced air blast slits or openings are formed 60 through the flat top wall of the grate bar and each opening is formed upwardly flaring by a surrounding downwardly and inwardly beveled edge 61, and each opening is centrally or diametrically bridged by a 65 depressed horizontal narrow bar or web 62. In these openings, I arrange suitable plates

tied down to the webs 62, by bolts 63, arranged centrally within the plates and openings. For instance, in the round openings, I show a removable ring 64, having a beveled edge corresponding generally to the 70 edge 61, and formed with edge stop points 65, to engage edge 61, so that when the ring is placed in the opening with the top face of the ring about flush with the top face of the grate bar, a narrow annular slit for discharge of air will be formed between edge 61, and the beveled edge of the ring. A separate removable cap 66, can be provided for each ring to close the open center of the ring except for intervening slits 67, for discharge of air between the cap and inner edge of the ring. The cap is provided with radial lugs 68, overlapping the ring and removably fitting in sockets depressed in the top face of the ring, to hold the same down 80 in position. The cap is formed with a central depending boss or stop 69, resting on the top face of the web 62. The bolt 63 passes centrally and removably through the cap and web 62, to hold or clamp the cap 90 down to the web. If so desired, the grate bar top can be formed with a series of spaced parallel elongated openings arranged transversely of the bar top provided with elongated beveled-edge removable plates 70, 95 flush with the bar top and forming the slits 71, around the plates and between their edges and the beveled edges of the openings, each plate 70 having a central depending stop boss 72, resting on the web 62, bridging the opening, and a removable central vertical confining bolt 73, passing through the plate, boss and web to hold the plate 100 down to its operative position.

In the event that fine ash or other dust 105 should drop through the slits and accumulate in the hollow grate bars, any suitable hooked-end poker or other manually operated instrument can be inserted through the furnace front and beneath the grate and 110 successively engage with the perforated lugs 58, to successively reciprocate the cleaner plates or slides 55, on the grate bar floors. As said slides are reciprocated the 115 holes 54, 56, will be periodically brought into registration, whereupon the compressed air in the grate bars will expel the dust and ashes downwardly through said holes into the ash pit of the furnace below the grate.

In the preferred formation of grate or 120 furnace bed shown by Fig. 1, each grate bar is supported by two beams 2, and the flat top head of each beam receives side supporting flanges 52, of two adjacent bars so that 125 the beam closes the space above the beam and between the grate bars from the space below the furnace bed, and the filling bricks 3, are laid transversely between the grate bars and on and upheld by the exterior ledges 51 of the adjacent bars, a distance 130

above flanges 52, and the beams 2. By this arrangement the beams 2, are insulated and protected from the heat of the furnace not only by the bricks 3, and packing 4, but also if so desired by dead air space 20. Any grate bar can be removed for repair or other purpose by removing the adjacent bricks and packing supported thereby and then lifting the bar from the beams without disturbing the remaining bars and bricks and packing.

It is evident that various changes might be resorted to in the forms, constructions and arrangements of the parts described and hence I do not wish to limit myself to the exact construction disclosed.

What I claim is:—

1. A forced-draft furnace bed comprising supporting beams, hollow grate bars parallel with and between and resting on said beams and extending upwardly above the horizontal plane of said beams and having top forced-draft outlets and filling material between said bars and closing the spaces above said beams and between the bars. 20

2. A forced-draft furnace grate comprising spaced supporting beams, hollow grate bars parallel therewith and having intermediate flanges resting on said beams, said bars having top draft outlets and side ledges, and bricks in the spaces between said bars and above said beams and supported by said ledges. 30

3. A hollow grate bar for a forced-draft furnace bed having top draft outlets and horizontal exterior opposite side flanges, and brick supporting ledges above said flanges. 35

4. A hollow grate bar having top air discharge openings, and throughout the length of its sides provided with longitudinal ledges for supporting filling material for closing the spaces between adjacent bars, and with longitudinal bar supporting portions, substantially as described. 40

5. A forced-draft furnace bed closed against the downward passage of fuel therethrough and comprising parallel spaced hollow grate bars having top air outlets, supporting beams arranged longitudinally of and parallel with and between said bars, and removable refractory material filling laid between said bars and above said beams to close the spaces between said bars. 45

6. A furnace bed comprising spaced supporting beams, hollow grate bars arranged longitudinally between said beams and projecting above the plane of the beams and having top air outlets and longitudinal side flanges resting on the beams and upholding the bars, and fuel-supporting means closing the spaces above said beam and flanges and between the top portions of said bars. 50

7. A closed forced-draft furnace bed comprising grate bar supporting beams, series of hollow grate bars arranged between and

resting longitudinally on said beams and having air outlets in their top fuel-supporting faces, said bars having side supporting ledges arranged above said beams and below their upper ends, and fuel supporting material closing the spaces between the top portions of the bars and supported by said ledges. 70

8. A closed forced-draft furnace bed comprising spaced supporting beams, hollow grate bars having top air outlets, said bars resting on said beams and arranged between the same and provided with side supporting portions adapted to uphold fuel supporting means, and fuel-supporting means closing the spaces between the bars and above the beams and forming dead air spaces above the beams and below the filling material, substantially as described. 75

9. A forced-draft furnace bed comprising spaced hollow grate bars having top air outlets and side supporting ledges below the horizontal plane of their upper ends, and bricks arranged in the spaces between the bars and laid on said ledges, substantially as described. 80

10. A hollow forced-draft grate bar having top air outlets and provided along its longitudinal sides with filling material supporting ledges, said bar formed of longitudinal sections fitted one within the other with their adjacent walls spaced apart to form an exterior cement receiving socket between the interfitting portions of the sections. 85

11. A closed forced-draft furnace bed comprising in combination, spaced hollow grate bars provided with top air discharge openings, supporting beams arranged between and parallel with said bars and below the tops thereof, and filling material arranged between the top portions of said bars and above and spaced from said beams thereby forming air spaces between the bars and above the beams and beneath said filling material. 100

12. A closed furnace bed comprising series of spaced parallel hollow grate bars provided with top air discharge openings, filling material closing the spaces between said bars and resting on and supported by the bars, and packing material laid thereon between the tops of the bars, substantially as described. 105

13. A closed forced-draft furnace bed comprising in combination, spaced supporting beams, hollow grate bars having top air discharge openings, said bars resting on arranged between, and parallel with said beams, and series of bricks spanning the spaces between the bars and above the beams. 115

14. A forced-draft furnace bed comprising in combination, spaced hollow grate bars having top air discharge openings, 120

- 1 closely arranged bricks spanning the spaces between said bars and resting on portions of the bars intermediate the height thereof.
15. A hollow grate bar for a forced-draft furnace bed consisting of a longitudinal bottom section forming an ash receiving trough open at the top and having depending side and end walls and a bottom floor and exterior lateral side supporting projections, 5 and a longitudinal top section having a flat fuel supporting top wall provided with air discharge openings, and depending side and end walls and an open bottom, the open top of the bottom section receiving the open 10 bottom of the top section to form the complete hollow bar, said ash receiving trough having means for discharging ashes therefrom.
16. In combination, in a forced-draft furnace bed, series of hollow grate bars each 20 consisting of two longitudinal sections, one of which is open at the top and forms an ash receiving trough provided with means for removing ashes from the interior thereof and the other section being hollow and open 25 at the bottom and having an approximately flat top fuel supporting wall provided with air blast openings and also formed with vertical side and end walls, and fuel supporting means closing the spaces between 30 the vertical side walls of said top sections of adjacent grate bars, the upper section of each grate bar being carried by the lower section thereof and at its lower edges fitted 35 thereto.
17. A forced-draft furnace bed comprising in combination, supporting beams, spaced hollow grate bars arranged between and longitudinally of said beams, and each 40 consisting of a longitudinal bottom section having exterior portions resting on two adjacent beams, and a longitudinal top section having air discharge openings in its top wall, said top section extending above said 45 lower section and at its lower portion fitted to said lower section, and filling material arranged between the top sections of the adjacent bars and above the lower sections of the adjacent bars.
- 50 18. A hollow grate bar for a forced-draft furnace bed having its top wall formed with a series of spaced openings and with a rigid web arranged longitudinally on its under side and extending across each opening, 55 means arranged in and approximately closing said openings to form air discharge slits and having depending bosses to engage said web, and bolts confining said means to said webs.
- 60 19. In combination, in a forced-draft furnace bed, hollow grate bars having top air discharge openings, closely arranged bricks spanning the spaces between said bars, and packing material laid on said bricks and 65 forming fuel supporting means between the top portions of the bars, substantially as described.
20. In combination, in a forced-draft furnace bed, series of supporting beams, series of hollow grate bars carried by said beams, 70 the beams being arranged in the spaces between the bars with the bars extending above the horizontal plane of the beams, fuel supporting means arranged between the upper portions of the bars and closing the 75 spaces between the same against downward passage of fuel, each bar having a top fuel supporting wall provided with air discharge openings, the lower portion of each bar forming an ash receiving trough provided with means for discharging ashes 80 therefrom.
21. A forced draft furnace bed having approximately flat level fuel supporting surfaces closing the bed against down draft and 85 fuel passage therethrough and comprising a hollow grate bar having a flat top fuel supporting wall formed with upwardly flaring air discharge slits and otherwise closed, said bar composed of upper and lower longitudinal sections, the bottom section having an unobstructed interior and forming an ash receiving trough provided with means for the discharge of ashes therefrom and having exterior side flanges, the top section 90 comprising said flat top wall and being fitted in and carried by said bottom section.
22. A forced draft furnace bed having approximately flat level fuel supporting surfaces closing the bed against down draft and 100 fuel passage therethrough and comprising a hollow grate bar having a flat top fuel supporting wall formed with upwardly flaring air discharge slits and otherwise closed, said bar composed of upper and lower 105 longitudinal sections, the bottom section forming an ash receiving trough having spaced ash discharge openings through its floor, a slide on said floor and normally closing said openings and having holes 110 adapted to register therewith for the discharge of ashes from said trough, and means extending to the exterior of the trough whereby said slide can be reciprocated, the top section comprising said flat top wall and 115 being fitted to and carried by said bottom section.
23. A forced draft furnace bed having approximately flat level fuel supporting surfaces closing the bed against down draft and 120 fuel passage therethrough and comprising a fixed hollow grate bar having a flat top fuel supporting wall formed with air discharge slits, said bar composed of upper and lower longitudinal sections, the bottom section 125 having an unobstructed interior and forming an ash receiving trough having a floor formed with spaced ash discharge holes, and a slide in said trough normally closing said holes and having openings adapted to regis- 130

ter therewith when the slide is reciprocated, the top section comprising said flat top wall and being fitted to and carried by said bottom section.

- 5 24. A hollow grate bar for a forced draft furnace bed having a flat top fuel supporting wall formed with spaced openings, flat plates fitted in said openings and in conjunction with the edges of the wall around 10 said openings forming air discharge slits, said top wall having portions bridging said openings close beneath said plates, means securing said plates to said portions and thereby leaving the interior of said bar unobstructed, said bar formed in longitudinal 15 sections, the bottom section forming an ash receiving trough and provided with means for the discharge of ashes therefrom, the top section comprising said wall and being 20 fitted to the bottom section.

25. A hollow grate bar for a forced draft

furnace bed closed against downward passage of fuel therethrough, said bar having a flat top fuel supporting wall formed with air discharge slits, and composed of longitudinal sections, the bottom section supporting the upper section and forming an ash receiving trough having an ash discharge opening and means normally closing the same, the top section comprising said top 25 wall and at its lower portion fitted in the upper portion of said bottom section, the adjacent walls of said sections spaced apart to form an exterior cement receiving socket between the interfitting portions of the sections, substantially as described.

In testimony whereof I affix my signature, in presence of two witnesses.

WILLIAM HOWARD PALMER.
